CONTROL CIRCUIT FOR RADIO TRANSMITTERS

Louis A. Gebhard, Washington, D. C., assignor, by
mesne assignments, to Wired Radio, Inc., New
York, N. Y., a corporation of Delaware

Application December 3, 1928, Serial No. 323,526

7 Claims. (Cl. 250—17)

My invention relates to transmitting systems in general and more specifically to control circuits of radio transmitters.

An object of my invention is to provide certain improvements in radio transmitters whereby an overload condition caused by improper control circuits prevents damage to the transmitting apparatus.

Another object of my invention is to provide a control circuit for a radio transmitter whereby the length of time that the control key may be depressed is automatically controlled.

A further object of my invention is to provide a control circuit adapted to open the keying circuit of a radio transmitter when the key circuit has been closed for a predetermined length of time and to completely remove all potential from the transmitting tubes when the key circuit continues closed for an additional length of time.

Other and further objects of my invention reside in the circuit arrangement a better understanding of which can be had from the specification following and by referring to the accompanying drawings wherein Figs. 1 and 2 are diagrams showing the control circuit for radio transmitters of my invention.

In radio transmitting systems employing thermionic tubes it is necessary to employ a source or several sources of electrical energy for energizing the respective electrodes of the tubes. In most installations it is the common practice to employ relays or contactors in circuit with the source of energy and the tubes as a means for starting and stopping the set. The relays or contactors may be controlled by a common circuit and a common source of electrical energy and the energization of one depending upon the pre-energization of another. Included in the common control circuit and the source of electrical energy a momentary contact switch may be employed by which the starting and stopping may be controlled. Such a system is schematically illustrated in the accompanying drawings wherein, thermionic tubes 1, 2 and 3, each having a plurality of electrodes which are energized by sources 5, 9 and 11. The cathodes of thermionic tubes 1, 2 and 3 are energized from source 5 by means of transformer 4. Relay 6 is provided with suitable contacting members, which when closed complete the energizing circuit to the primary circuit of transformer 4. The anodes of thermionic tubes 1, 2 and 3 are energized from source 9 by means of contacting members associated with the armature of relay 10. The energization of relays 6 and 10 is dependent upon the

pre-energization of relay 8. The energization of relay 8 is dependent upon the closing of momentary contact switch member 7. Source of potential 11 is provided for energizing the respective control electrodes of thermionic tubes 1, 2 and 3.

In transmitting systems for the transmission of code some method must be employed for starting and stopping oscillations or an equivalent result the starting and stopping of the amplifier tubes. It is well recognized by those skilled in the art that a satisfactory method of keying employs a source of negative control electrode bias supplied to tubes, which bias is lowered in value when transmission of a code character is desired. Such a method of keying is illustrated in the accompanying drawings. In the schematic circuit arrangement shown in Fig. 1 of the accompanying drawings, the control electrode of thermionic tube 2 is controlled by this method. The control electrode of thermionic tube 2 is normally supplied with energy from source 11 by means of resistor 12b and the return circuit including the cathode. The potential supplied the control electrode may be of a negative polarity in respect to the polarity of the cathode. The value of potential with a given source would be governed by the value of resistor 12b. A resistor 12c is connected in parallel with source 11 and a connection made thereon near the cathode potential end. This connection leads to the contacting member associated with armature 12a of electromagnet 12. A contact member positioned adjacent to armature 12a provides a complete circuit from the control electrode of thermionic tube 2 to resistor 12c. The value of negative potential supplied the control electrode of thermionic tube 2 may be of a much lower value when the supply of energy is from source 11 by means of the contacting members. This change in the potential supplied the control electrode of thermionic tube 2 causes the operating characteristics of the tube to be proper for efficient amplification of the energy from thermionic tube 1. Electromagnet 12 is energized from source of energy 13. The closing of key 14 completes the energization of electromagnet 12 and the actuation of armature 12a. The solenoid 15 of a retardard relay is connected to source of energy 13 and key 14. Solenoid 15 is energized by means of closing key 14 thereby completing the circuit to source of energy 13. Solenoid 15 is electromagnetically associated with an armature 16. Armature 16 is provided with a suitable retarding device 16a which may comprise a dash-pot as shown or any suitable bellows arrangement. An insulated arm 17 is positioned

to armature 16 and is provided with suitable contacting members 18 and 18a. Contacting members 18 normally complete the key circuit from source 13 through key 14 to electromagnet 12. 5 Contacting members 18a are normally closed thereby allowing the energization of relays 6, 8 and 10 by the closing of momentary contact switching member 7. The opening of contacting members 18 and the opening of contacting members 18a is retarded by dash-pot 16a.

10 The opening of contact members 18 precedes the opening of contact members 18a. Fig. 2 of the accompanying drawings shows individual retarded armatures 16 and 16a with which are associated individual contact members 18 and 18a. Each of the armatures have different retardation properties.

Fig. 1 of the accompanying drawings shows contact members 18 and 18a associated with a 20 common armature 16. In the ordinary course of keying the energization of electromagnet 12 is completed. If, however, key 14 is depressed for a predetermined length of time, armature 16 will overcome the retardation effect of dash-pot 16a and contact members 18 will open the circuit thereby causing no energization of electromagnet 12 with the depression of key 14. If key 14 is depressed for an additional length of time after the opening of contact members 18, contact members 18a are then opened which opens the circuit and deenergizes relays 8, 6 and 10. The deenergization of relays 8, 6 and 10 removes all potential from thermionic tubes 1, 2 and 3. When the key is depressed for an unnecessary length 35 of time by an operator or a closed circuit in the remote control line occurs, the keying circuit is opened. If the key circuit continues closed the complete transmitting set is closed down.

I realize that many modifications of the control 40 circuit for radio transmitters of my invention are possible without departing from the spirit of my invention. Contact members may be provided on a suitable retarded armature whereby the circuit is completed when the armature is actuated. The completion of the circuit can be arranged to short circuit an electromagnet and thus deenergize the set.

It is to be understood that many modifications 50 of the control circuit for radio transmitters of my invention other than as shown in the representative circuit arrangement illustrated in the accompanying drawings are possible without departing from the spirit of my invention and it is not intended to restrict the embodiments of my invention to the foregoing specification or the

accompanying drawings but only as defined in the accompanying claims.

What I claim as new and desire to secure by Letters Patent of the United States is as follows:

5 1. In an electron tube system, an electron tube having a plurality of electrodes, a conditioned circuit, controlling means for supplying a predetermined potential to one of said electrodes, other energy controlling means for supplying energy to other of said electrodes, and control means responsive to certain predetermined conditions in said conditioned circuit for controlling said first mentioned control means and responsive to further and subsequent predetermined conditions of said condition circuit for effecting the control of said other control means.

10 2. The combination in accordance with claim 1 in which said conditioned circuit includes signal modulation means and in which said predetermined conditions correspond to predetermined conditions in said signalling circuit.

15 3. The combination in accordance with claim 1 in which said first mentioned electrode comprises the control electrode and said first mentioned energy controlling means supplies biasing potential thereto.

20 4. The combination in accordance with claim 1 in which said other of said electrodes includes at least a cathode and an anode, and in which said second mentioned control means controls the energization of said electrodes.

25 5. The combination in accordance with claim 1 in which said first mentioned electrode and said first mentioned control means comprises biasing energization means, and in which said other of said electrodes includes at least a cathode and anode and in which said second mentioned control means comprises energization means for said electrodes.

30 6. The combination in accordance with claim 1 in which said conditioned circuit includes a key and time controlled relay responsive to different predetermined durations of closure of said key.

35 7. The combination in accordance with claim 1 in which said conditioned circuit includes a key and time controlled relay means responsive to different durations of closure of said key, said first mentioned electrode comprises a control electrode, said first mentioned controlling means comprises biasing energization means for said electrode, said other electrodes include at least a cathode and an anode, and said second mentioned control means includes energization means for said electrodes.

LOUIS A. GEBHARD.
